UNITED STATES PATENT OFFICE.

HARRY H. WOOD, OF SEATTLE, WASHINGTON, ASSIGNOR OF ONE-HALF TO DON H. PALMER, OF SEATTLE, WASHINGTON.

BAG-HOLDING DEVICE.

Application filed October 25, 1921. Serial No. 510,404.

To all whom it may concern:

Be it known that I, HARRY H. Wood, a citizen of the United States, residing at Seattle, in the county of King and State of Washington, have invented certain new and useful Improvements in Bag-Holding Devices, of which the following is a specification.

This invention relates to a device adapted 10 to be used at the bedside of a patient for holding paper bags or receptacles to receive soiled paper napkins.

Receptacles of this character have heretofore been attached by means of pins in an 15 insecure manner to the bedding or mattress of a patient's bed.

Such a manner of supporting a bag has, moreover, proved unsatisfactory by lack of any means for maintaining the same in a 20 distended position so as to obviate the necessity of a patient using more than one of his hands to deposit a napkin in the bag.

The object of the present invention is to overcome the above and other inconveniences or causes of trouble by the provision 25 of simple and inexpensively constructed bag holding and supporting devices which are efficient in use.

The invention consists in the novel construction, adaptation and combination of 30 parts hereinafter described and claimed.

In the accompanying drawings,—

Figure 1 is a perspective view of a bag-holder embodying my invention shown applied. Fig. 2 is a side elevation of a portion 35 of the bag holder with a bed rail in transverse section. Fig. 3 is a detached perspective view of a portion of the holder proper; and Fig. 4 is a similar view of the holder bed-attachment.

In said drawings, the reference numeral 5 represents an angle-bar side rail of a metal 40 bedstead such as commonly used in sanatoriums and hospitals. This type of bed rail is formed with horizontal and vertical flanges 6 and 7, respectively, and in proximity to one end of the bed said rail may be provided with a superimposed rack 8 for the prop member, not shown, of a back rest.

In carrying out my invention, I employ a 50 bed attachment, indicated generally by 9, comprising a plate which is bent or otherwise formed to provide a vertical body portion 10 adapted to fit against the rail flange 7 and having at the top and bottom of the

body laterally directed portions 11 and 12. The part 11 serves as the supporting member of the attachment by seating upon the rail flange 6 and to accommodate a back rack 8, where used, the part 11 is provided 60 intermediate its length with an upwardly extending looped portion 13. The rear end of the part 11 is formed to provide a downwardly directed flange element 14 adapted to hook over the rear edge of the rail flange 65 6 and is desirably turned under the latter as indicated by 14' in Fig. 2. The part 12 of the attachment extends horizontally, or nearly so, below the bed rail and at its sides is formed to provide hook-shaped elements 70 15 to afford opposing recesses 16 as shown in Fig. 4.

Included in the invention is a bag holder which is advantageously formed of a single 75 piece of wire which is bent to provide at its midlength a horizontally disposed rectangular frame comprising a front element 17, side elements 18 and complementary rear elements 19 which extend from the rear corners 20 to bends 21 and thence rearwardly 80 as at 22, to bends 23 wherefrom the wire parts extend downwardly to constitute a shank 24.

To render said shank more rigid the wire 85 parts thereof are desirably twisted or braided together as at 25. Below such twisted portion the strands are spread apart to provide vertically arranged branch elements 26 which terminate in rearwardly directed parallel arms 27 having outwardly directed extremities 28. The branch elements 26 at the lower portion of the shank are arranged to 90 yieldingly retain the arms 27 at a greater distance apart than the width of the attachment part 12 in order that the resiliency of 95 the branches will act to hold the arms within the recesses 16 of the respective hook elements 15.

The lengths of said arms between the 100 branch elements 26 and the hooked extremities 28 thereof are equal to the lengths of the attachment parts 15 so that the hook extremities of the arms obviate the accidental withdrawal of the holder from the attachment 105 and will also serve to retain the branches 26 of the holder shank in juxtaposition with the body portion 10 of the attachment.

29 represents a paper bag which is to be suspended from the holder and is connected thereto by having the bag material about the 110

mouth folded, as at 30, over the frame elements of the holder and, being thus connected, the bag is secured preferably by means of spring metal clips 31 of substantially U shapes in cross section.

It is to be noted that my improved device serves to hold a bag 29 in its distended position and within convenient reach of a patient lying upon the associated bed.

- 10 When desired, a bag is removed to be destroyed with its contents by burning in a furnace. Bags are readily removed or replaced without disconnecting the holder from the attachment 9 or the latter from the bed. When the holder is not required, however, it may be readily withdrawn by drawing the arms 27 toward each other to disengage the same from the attachment recesses 16.
- 15 20 While I have illustrated the preferred embodiment of my invention, I do not wish to be understood as intending to limit myself to the specific construction shown, as variations or modifications therefrom may be made without departing from the spirit of the invention within the scope of the appended claims.

What I claim, is,—

- 20 30 35 40 1. In a device of the character described, the combination with a support, of an attachment adapted to engage over the top of said support and having a socket, a bag holder made of a single piece of wire bent to form a substantially horizontal frame element and having a pair of rearwardly extending arm elements disposed at a lower elevation than said frame element and engageable in the socket of said attachment.
2. In a device of the character described, the combination with a support, of an attachment adapted to engage over the top of said support and having a socket below the

support, a bag holder made of a single piece of wire bent to provide a vertical shank element with a substantially horizontal frame element at its upper end and a pair of rearwardly extending arm elements at its lower end which are engageable in the socket of said attachment, said arm elements being bent to provide opposite laterally-projecting extremities for retaining the arms in their engagement with said attachment.

3. In a device of the character described, the combination with a support, of an attachment adapted to engage over the top of said support and having a socket located below said support, of a bag holder made of a single piece of wire bent to form a substantially horizontal frame member, a shank depending from the rear of said member and having at its lower end a pair of rearwardly extending arm elements which are engageable in the socket of said attachment.

4. In a device of the character described, the combination with a support, of an attachment adapted to engage over the top of said support and having a socket member, of a bag holder made of a single piece of wire bent to form a substantially horizontal frame member, a shank depending from the rear of said frame member and having a pair of rearwardly extending arm elements engageable in the socket member of said attachment, said arm elements being bent to provide opposite laterally-projecting extremities for retaining the arms in their engagement with said attachment.

Signed at Seattle, Washington, this 18th day of October, 1921.

HARRY H. WOOD.
